(57) CLAIM

The ornamental design for a miniature golf bag travel organizer, as shown and described.

DESCRIPTION

FIG. 1 is a perspective view of the miniature golf bag travel organizer showing my new design;

FIG. 2 is a right side view thereof;

FIG. 3 is a front view thereof;

FIG. 4 is a left side view thereof;

FIG. 5 is a top view thereof; and,

FIG. 6 is a bottom view thereof.

The present application is directed to the design illustrated in the drawings. The broken line portions of the disclosure are for illustrative purposes only and form no part of the claimed design.
